UNITED STATES PATENT OFFICE

MATHEW B. MORGAN, OF DETROIT, MICHIGAN, ASSIGNOR TO THE TIMKEN-DETROIT AXLE COMPANY, OF DETROIT, MICHIGAN, A CORPORATION OF OHIO

AIR COMPRESSOR

Application filed August 24, 1929. Serial No. 388,048.

This invention relates to fluid pumps and is particularly applicable to air compressors. Its principal objects are to devise an air compressor that will be economical to produce, maintain and operate, that will be quiet and positive in action, that will be compact, strong, durable and of large capacity, and that will be adjustable for varying its output. Another principal object is to improve the lubrication and particularly to keep the lubricant from getting into the fluid delivered by the pump. The invention consists in the parts and in the arrangements and combinations of parts hereinafter described and claimed.

In the accompanying drawing, which forms part of this specification and wherein like numerals refer to like parts wherever they occur,

Fig. 1 is a longitudinal sectional view, partly in elevation, of an air compressor embodying my invention, the sections being taken on the line 1—1 in Fig. 2,

Fig. 2 is a transverse cross-section on the line 2—2 in Fig. 1,

Fig. 3 is an end elevation with parts shown in transverse section,

Fig. 4 is a longitudinal sectional view of the cam member; and

Fig. 5 is a diagram illustrating a complete cycle of operation for each revolution of the piston around the axis of the shaft.

The present device comprises a short cylindrical or annular member 1, hereinafter called a cam member, with a cylindrical inner surface on which is a continuous rib 2 which is arranged obliquely with reference to the longitudinal axis of said surface, and constitutes a cam. The sides of said rib are beveled. Each of a number of cylindrical pistons or piston members 3 (four in the construction shown) is provided midway of its length with a circumferential groove 4 with beveled sides and of proper width to

roll freely over the cam rib 2. Each end of each piston fits in a cylindrical chamber 5, hereinafter called a piston chamber, formed in the marginal portion of a rotor 6 composed of two aligned counterpart members 7 of cylindrical form. Each of said cylin-

drical members has as many piston chambers as the number of pistons, such chambers being disposed longitudinally in said member and equi-distant from each other.

The inner ends of said cylindrical member 7 abut against each other except at their peripheral portions, where they are recessed sufficiently to receive the cam member 2 freely between them. The outer ends of said cylindrical members are closed by end caps 60 or closure plates 8 that are clamped firmly together by long threaded bolts 9 that extend through said cylindrical members and are tightened by nuts 10 therein. Said cylindrical members are accurately centered by 65 dowels or pins 11 in their meeting faces, with their piston chambers in alinement; and the outer ends of said cylindrical members have axial openings which fit over centering lugs 12 provided therefor in the inner 70 faces of the closure plates. Each closure plate has a stub shaft 13 formed integral therewith.

The two stub shafts 13 are journaled in bushings or antifriction bearings 14 mounted 75 in hubs 15 provided therefor in the ends of a stationary casing 16. The casing is made of two hollow cylindrical members 17 closed at their outer ends and open at their inner ends. The casing members fit over the rotor 6, with 80 their inner ends bearing over and against the cam member 1 whose ends are recessed to receive said casing members. Said casing members 17 are secured together by long bolts 18 that extend endwise through them 85 and the intervening cam member 1 and are provided with nuts 19 on their threaded ends. The closed ends of said casing members are formed into the hubs 15 adapted to receive the bearings 14 for the stub shafts 13 that 90 are integral with the closure plates of the rotor. One of said stub shafts is suitably connected to a source of power to be driven thereby.

It is apparent from the foregoing description that when power is applied to the rotor, said rotor is rotated on its axis carrying the several pistons with it. As the pistons continuously engage the cam rib 2, which is stationary, the revolution of the pistons about 100

the axis of the shaft causes such pistons to move endwise in their chambers an amount equal to the throw of the cam rib; and it is this reciprocating movement of the piston that is utilized for pumping or compressing.

All of the pistons operate alike; and the timing of one of them is illustrated by the diagram shown in Fig. 5 wherein there is a complete cycle of operation for each revolution of the piston around the axis of the shaft.

10 In the design illustrated, air or other fluid is admitted into one end of the cylinder throughout 135° of such revolution, and such air or fluid is compressed for the next 170° and is then exhausted through the next 20° , after which the exhaust is closed and suction permitted for 35° before the renewal of the cycle. The same cycle of operation is repeated at the opposite end of the same piston, but 15 the phase of the cycle at one end of the piston is 180° different from the phase at the other end of said piston.

In order to provide for such operation, a radial port 21 is formed in the side wall of 20 each piston chamber in position to register with a circumferentially elongated groove 22 (about 135° in the example) in the inner cylindrical surface of the casing, which groove communicates through a passageway 23 in the casing to the source of fluid supply. The portion of the piston opposite said port is of reduced diameter, such reduced portion 25 being of such width that said port is always opposite some portion thereof. Cross bores 25 are formed in the piston in the portion of reduced diameter and communicate with an axial bore 26 that extends to the end thereof. By this arrangement, the groove 22, which is in communication with the 30 source of fluid supply remains in communication with the admission port of each piston chamber throughout 135° of its revolution, and during this period the fluid passes from the groove to the radial port of the piston chamber and thence through the annular space surrounding the reduced portion of the piston into the cross ports of the piston and thence through the longitudinal bore in the piston into the end of the piston chamber.

40 As soon as the radial port of the piston chamber passes the end of the groove in the casing, communication with the source of fluid supply is cut off, the fluid charge is trapped in the piston chamber, and the operation of 45 compression thereof begins and continues until the opening of the exhaust port.

The exhaust passageway 27 extends longitudinally of the wall of the casing and opens 50 into a circumferentially elongated groove 28 in the inner wall thereof. In the example, this exhaust groove extends through an angle of about 20° . Opposite this exhaust groove is the port or passageway 21 that extends through the wall of the piston chamber opposite the reduced portion of the piston. By

this arrangement, the charge of air or other fluid that is compressed in the end of the piston chamber is discharged through the longitudinal and cross passageways in the piston to the space surrounding the reduced portion of said piston and thence through the port in the wall of the piston chamber and the discharge passageway in the casing.

Lubrication of the pistons is effected by oil or other lubricant admitted through a hole 29 in the upper part of the casing into the space between the recessed peripheral portions of the two cylindrical members of the rotor, where the lubricant is in direct contact with the cam rib 2 and the exposed middle portions of the piston members, including the cam engaging grooves therein. As the cam rib remains stationary while the piston working in engagement therewith revolves around the axis of the shaft, there is enough friction between them to cause rotation of the piston members on their respective axes. Advantage is taken of this fact to overcome the tendency of the lubricant to get into the charge of fluid. For this purpose, the cylindrical surfaces of each piston member adjacent to the main groove 4 thereof which operates with the cam rib are provided with small helical grooves 30 that start at the wall of said main groove and preferably make several turns around the piston member. The two oil grooves are of opposite hand to each other and their lead is such that, as the piston member rotates on its axis in its normal direction, the points of intersection of the two oil grooves with any given longitudinal plane continuously approach each other. Thus their inclination or direction is such that they tend to fling the oil toward the main groove and thus tend to keep the oil or lubricant from creeping into the chamber beyond the end of the piston.

While the device hereinbefore described is especially adapted to be run at high speed for compressing air, it is adapted for use with other compressible fluids; and by properly correlating the intake and discharge passageways in accordance with common practice, said device may be found used for pumping liquids.

For the purpose of regulating the compressor, provision is made for shifting the cam member 1 circumferentially with relation to the other casing members. For this purpose, it is only necessary to loosen and remove the clamping bolts, turn the cam member to bring new holes therein into register with the holes in the casing members, pass the bolts through them and tighten the nuts thereon. Of course, the holes through the cam member are arranged in groups of the same number as the bolts and distributed so that all of the members of each group will simultaneously register with the bolt holes in the cas-

It is noted that the device is very compact, that its parts are easy and simple to manufacture and assemble, that the device is well balanced and well adapted to run at high speed, that all of its parts are simple, strong and durable; that its lubrication system is simple and efficient and protects the fluid charge against contamination with lubricant, that the discharge is subject to considerable range of adjustment, and that there is little likelihood of any of the parts getting out of order.

What I claim is:

1. A pump comprising a casing having fluid distributing passageways therein and having a continuous cam rib on the interior thereof, a cylindrical rotor rotatable in said casing and having a plurality of piston chambers arranged therein in alined pairs, and a reciprocatable piston member for each pair of chambers, each piston member having a circumferential groove at the middle thereof adapted to receive said cam rib and each piston member having a portion of reduced diameter in each end portion thereof and a passageway from said reduced portion through the end of said piston member, and the rotor having passageways opening into the respective piston chambers opposite the reduced portions of the piston members and arranged to communicate periodically with said first-mentioned passageways, respectively.

2. An air compressor comprising a casing having fluid distributing passageways therein and having a continuous cam rib on the interior thereof, a cylindrical member rotatable in said casing and having a plurality of piston chambers therein, a reciprocatable piston in each chamber having a circumferential groove near the middle thereof adapted to receive said cam rib and passageways communicating with said first-mentioned passageways, respectively, opening into the respective piston chambers, each piston having a distributing groove encircling it and a passageway from said groove through the end thereof.

3. A pump comprising a casing having fluid distributing passageways therein and having a continuous cam rib on the interior thereof, and a cylindrical rotor rotatable in said casing and having a plurality of piston chambers therein, and a reciprocatable piston in each chamber having a circumferential groove near the middle thereof engaging said cam rib, said rotor having passageways arranged to communicate periodically with said first-mentioned passageways respectively and opening into the respective piston chambers, each piston having a portion of reduced diameter opposite the adjacent rotor passageway and also having a passageway from such reduced portion through the adjacent end of said piston.

4. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said casing and said rotor and said piston being provided with appropriate passageways for pumping, said casing comprising an annular member on the inner face of which is said cam rib and two cylindrical members abutting against said cam member and having journal bearings on their outer ends for said rotor, and said rotor comprising counterpart cylindrical members adapted to fit in said casing with their inner ends abutting against each other and with the peripheral portions of said inner ends recessed to freely accommodate said cam member, said rotor also comprising end closure plates that are provided with shafts that are journaled in said bearings, and longitudinal clamping bolts clamping said end plates together.

5. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said casing and said rotor and said piston being provided with appropriate passageways for pumping, said casing comprising an annular member on the inner face of which is said cam rib and two cylindrical members abutting against said cam member and having journal bearings on their outer ends for said rotor, said cam member and said end members having longitudinal symmetrically arranged holes and fastening bolts extending through said holes whereby said parts may be adjusted circumferentially with relation to each other, and said rotor comprising counterpart cylindrical members adapted to fit in said casing with their inner ends abutting against each other and with the peripheral portions of said inner ends recessed to freely accommodate said cam member, said rotor also comprising closure plates that are journaled in said bearings.

6. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said casing and said rotor and said piston being provided with appropriate passageways for pumping, said casing comprising an annular member on the inner face of which is said cam rib and two cylindrical members abutting against said cam member and having

journal bearings on their outer ends for said rotor and means for securing said members together with said annular member in either of a plurality of different positions of 5 rotary adjustment.

7. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said casing and said rotor and said piston being provided with appropriate passageways for 10 pumping, said casing comprising an annular member on the inner face of which is said cam member and two cylindrical members abutting against said cam member and having journal bearings on their outer ends for said 15 rotor, said cam member and said end members having longitudinal holes, and fastening bolts extending through said holes.

8. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said 20 casing and said rotor and said piston being provided with appropriate passageways for pumping, said casing comprising an annular member on the inner face of which is said cam rib and two cylindrical members abutting 25 against said cam member and having journal bearings on their outer ends for said rotor, said cam member and said end members having longitudinal symmetrically arranged holes, and fastening bolts extending through 30 said holes whereby said parts may be adjusted circumferentially with relation to each other.

9. A pump comprising a casing having a continuous cam rib on the interior thereof, a cylindrical rotor rotatable in said casing and having a plurality of piston chambers therein, and a reciprocatable piston in each chamber having a circumferential groove near the middle thereof engaging said cam rib, said 45 casing and said rotor and said piston being provided with appropriate passageways for pumping, said casing comprising an annular member, on the inner face of which is said cam rib, and two cylindrical members abutting 50 against said cam member and having journal bearings on their outer ends for said rotor, said cam member and said end members having longitudinal symmetrically arranged holes, and fastening bolts extending 55 through said holes whereby said parts may be adjusted circumferentially with relation to each other, and said rotor comprising counterpart cylindrical members adapted to fit in said casing with their inner ends abutting against each other and with the peripheral 60 portions of said inner ends recessed to freely accommodate said cam member, said rotor also comprising closure plates that are provided with shafts that are journaled in said bearings, and longitudinal clamping bolts 65 clamping said end plates together.

10. A pump comprising a casing having a continuous cam rib on the interior thereof, a cylindrical rotor rotatable in said casing and having a plurality of piston chambers 70 therein, and a reciprocatable piston in each chamber having a circumferential groove near the middle thereof engaging said cam rib, said casing and said rotor and said piston being provided with appropriate passageways for pumping, said casing comprising an annular member on the inner face of which is said cam rib and two cylindrical members abutting against said cam member and having journal bearings on their outer ends for 75 said rotor, said cam member and said end members having longitudinal symmetrically arranged holes, and fastening bolts extending through said holes whereby said parts may be adjusted circumferentially with relation to each other, and said rotor comprising counterpart cylindrical members adapted to fit in said casing with their inner ends abutting against each other and with the peripheral portions of said inner ends recessed to freely accommodate said cam member, said rotor also comprising closure plates that are provided with shafts that are journaled in said bearings, and longitudinal clamping bolts 80 clamping said end plates together.

11. A pump of the kind described comprising a casing which comprises an annular cam member having a continuous cam rib on the interior thereof and two alined cylindrical members on opposite sides of said cam member, a cylindrical rotor rotating in said casing and comprising counterpart cylindrical members adapted to fit in said casing with their inner ends abutting against each other and with the peripheral portions of said inner ends recessed to accommodate the cam rib portion, each of said rotor members having a plurality of piston chambers therein alined with the piston chambers of the other rotor members, reciprocatable piston members each having a circumferential groove in the middle thereof engaging said cam rib and with its end portions working in alined piston chambers.

12. A pump of the kind described comprising a casing comprising an annular cam member having a continuous cam rib on the interior thereof and two alined cylindrical members on opposite sides of said cam member, a cylindrical rotor rotating in said casing and comprising alined cylindrical members adapted to fit in said casing with their inner ends abutting against each other and with the peripheral portions of said inner ends recessed to accommodate said cam member, each 105

110

115

120

125

of said rotor members having a plurality of piston chambers therein alined with the piston chambers of the other rotor members, reciprocatable piston members each having a circumferential groove in the middle thereof engaging said cam rib and with its end portions working in alined piston chambers, said casing having a passageway for lubricant opening into the space adjacent to said cam rib, and said piston member having helical grooves of opposite hand extending from the main groove thereof, the hand of each helical groove being such that its point of intersection with any longitudinal plane approaches the main groove as the piston rotates in normal direction.

13. A pump of the kind described comprising a casing having a continuous cam rib on the interior thereof, a cylindrical rotor rotat-
ing in said casing and comprising counter-
part cylindrical members adapted to fit in
said casing with their inner ends abutting
against each other and with the peripheral
portions of said inner ends recessed to accom-
modate the cam rib portion, each of said rotor
members having a plurality of piston cham-
bers therein alined with the piston chambers
of the other rotor members, reciprocatable
piston members each having a circumferen-
tial groove in the middle thereof engaging
said cam rib and with its end portions work-
ing in alined piston chambers, said casing
having a passageway for lubricant opening
into the space adjacent to said cam rib, and
said piston member having helical grooves of
opposite hand extending from the main
groove thereof, the hand of each helical
groove being such that its point of intersec-
tion with any longitudinal plane approaches
the main groove as the piston rotates in nor-
mal direction.

Signed at Detroit, Michigan, this 19th day
of August, 1929.
